UNITED STATES PATENT OFFICE.

HERBERT E. WALKER, OF CHICAGO, ILLINOIS.

THREADED-CLAMP CONNECTER FOR STORAGE BATTERIES.

Application filed August 6, 1921. Serial No. 490,315.

This invention relates to a novel connector for connecting the post of a storage battery with the lead or conductor through which the current is conducted to and from the battery in charging and discharging the latter.

Among the objects of the invention is to provide an improved connector for this purpose to form a good electrical contact between the connector and the post, by means which produce a compact and rugged construction.

A further object of the invention is to provide a novel means for clamping directly on the post a part of the connector which surrounds the post, the construction embracing wedge-like threaded parts which, when forced home, afford reliable electrical contact between the detachable parts.

Another object of the invention is to provide a novel connector of this character in which the part that surrounds the post has the form of a split member and which constitutes part of the current path, and which is adapted to be fitted axially over the post and to be clamped thereon by a threaded nut, the coacting parts of the structure being relatively tapered to clamp its current conducting parts together.

Another object of the invention in respect of the phase last mentioned is to so construct a split ring with respect to the hand of the screw thread that when the nut is turned over the split ring, the friction contact of the threads of the nut and ring tends to wrap the ring member about the post to afford superior frictional contact between the post and ring.

Other objects of the invention are to further improve and simplify connectors for the general purposes set forth, and the invention consists in the combination and arrangement of the parts shown in the drawings and described in the specification, and is pointed out in the appended claim.

It will be understood that the connector shown may be employed with any type of battery having outstanding posts through which connection is made from the interior to the exterior of the battery, and vice versa, and that the connector may embody varying forms of cable terminal sockets.

As shown in the drawings:—

Figure 1 is a partial plan view of a cap

cover for an electric storage battery box, 55 showing one of the connectors and the associated cap for closing the water inlet.

Figure 2 is a plan view of the connector with the nut removed.

Figure 3 is a section on the line 3—3 of 60 Figure 2, with the post shown in elevation.

Figure 4 is a similar section on the line 4—4 of Figure 3.

Figure 5 is a section of a modification, showing a slightly different form of terminal socket.

First referring to the construction shown in Figures 1 to 4, inclusive, 10 designates the top cover of a storage battery box. 11 designates the cap for closing the water opening, and 12 designates, as a whole, my improved connector.

Referring to Figures 2, 3, and 4, 14 designates the battery post which is fixed in any suitably known manner to the cover 10. 75 Said connector comprises in general terms, a ring member 15, which can be made integral with the cable terminal socket 16, as by means of a neck or connecting portion 17. The socket 16, shown in Figure 2, is an angle socket, and, as shown, is of that type in which the cable terminal may be soldered therein. In Figure 5 is shown a somewhat different form of connector, the socket 18 being of that type generally known as a 80 universal socket that has a through opening 19 disposed axially of the socket member to receive a cable terminal fitting from either end, and is provided with a threaded opening to receive a clamping screw 20, by 90 which the terminal fitting can be clamped in the socket member.

In the connector shown in Figures 1 to 4, inclusive, the ring 15 embraces a relatively massive base member 21 and a thinner upwardly threaded. The said base and shell of the ring may be interiorly tapered to engage over the exteriorly tapered post 14. The shell portion 22 of the ring is provided with 100 a plurality of angularly spaced slits 23 which extend through the top margin thereof and down to the base 21. One of said slits 23 is in line with and constitutes a continuation of the slit 24 which is formed 105 transversely of the base from its margin to its bore so that thereby the ring is slotted throughout its length at one point.

25 designates a nut, preferably end closed to constitute a cap nut. It is interiorly screw threaded and fits over and engages the exterior screw thread of the shell 22 of 5 the ring 15. The threaded portions of said nut and shell are relatively tapered so that when the nut is threaded down over the shell the segments of the shell between the slits 23 are forced inwardly in close electrical contact with the post so as to frictionally lock the ring over the post and produce a good electrical joint between the ring and post, and to lock the parts rigidly together. As herein shown, the threaded portion of 10 the shell is exteriorly tapered, while the interior thread of the nut is formed on the cylindric face thereof. In other words, the shell thread is tapered and the nut thread is straight. Therefore, the coaction of the 15 straight and tapered threads force the segmental part of the nut shell closely against the post.

As a further improvement, the slit 24 which is cut through the base of the ring 15 25 is located in a part of the ring base adjacent to the fixed connection between the ring and the terminal socket 16, or the part of the ring structure which is most rigid, and the hand of the thread on the shell portion of the ring is in a direction tending from one side of said socket connection, and extending throughout the greater part of the circumference of the ring toward said slit, as indicated by the arrow on 30 Figure 2. With this construction it will be manifest that when the nut has been turned down tightly on the ring, the friction of the nut on the threaded portion of the ring grasps the slotted ring part which operates 35 to pull or wind the ring about the post from the connection of the ring with one side of the terminal socket towards the direction indicated by said arrow in Figure 2. The friction pull will also be exerted through the 40 base and cause such winding effect to be exerted throughout the depth of the ring, the slit 24 narrowing during such winding operation. Such winding of the ring about the post is permitted, not only by reason of 45 the hand of the thread relatively to the position of the slit 24, but also by reason of the relatively soft metal of which the ring is formed, brass, suitably plated, being material which may be used.

50 It will be obvious that by reason of the slotted threaded shell of the ring, the segments of which are forced inwardly against the post by the relatively straight and tapered threads on the shell and nut, and by 55 reason of the hand of the nut operating in connection with the slotted shell and base to wrap the ring about the post, a very intimate contact between the nut and shell may be thus attained.

60 Ordinarily, such intimate contact would

not be easy to break, when it is desired to detach the connector from the post, by reason of tendency or corrosion or freezing between the ring and post. However, the relatively wide slit 24 in the post of the ring permits 65 an instrument, such as a screw driver, to be inserted in said slit to separate the ring parts at the side of said slit. Alternatively, the straight threads may be formed on the ring shell, and the tapered threads on the 70 nut. So also the bore of the ring may be made cylindric to fit a straight post.

In the construction shown in Figure 5, the post 26 is tapered and exteriorly threaded. In this construction the ring member 27 75 is solid or unslotted. Said ring is interiorly smooth, as shown at 29, and of greater diameter than the tapered threaded portion of the post.

80 30 designates a nut preferably closed at its end. Said nut is provided with an exterior cylindric perimeter 31, and an interior tapered thread 32. The skirt of the nut is provided with angularly spaced longitudinal slits 33 around its perimeter 85 to form deformable segments between said slits in the same manner as like segments are formed in the slit shell portion of the ring in the construction shown in Figures 90 1 to 4, inclusive.

95 In the construction shown in said Figure 5, the ring 27 is fitted loosely over the threaded end of the post 26. The shell like portion or skirt of the nut is then fitted at its lower narrower portion into the space 100 between the tapered threaded end of the post and the internal cylindric surface 29 of the ring, and the ring is locked in place by threading the nut down over the post. It will be noted that the cross section of 105 the threaded part of the nut is that of a wedge, and as the nut is threaded down over the post said wedge formation acts on the slotted wedge-shaped skirt of the nut to expand the smooth perimeter 31 thereof into 110 intimate contact with the internal plain cylindric face 29 of the ring to afford close contact between said surfaces and also to rigidly lock the parts together.

115 In both of the constructions shown, it will be noted that the nuts are provided with polygonal upper extremities for ready engagement by a wrench, or the like, for turning the nut downwardly to clamp the 120 contacting faces together and for removing the nut. It is also obvious that both embodiments of the invention provide an extremely rugged connector which is capable of hard usage without impairing the parts thereof, which locks the structure assembled, and which press the engaging faces into good electrical contact. It is also obvious the construction is such that the connector can be quickly removed from the 125 post and attached thereto, inasmuch as the 130

nut is accessible for the free use of a wrench to turn the same on and off. The construction is compact in both vertical and lateral dimensions because of the slotted construction of the threaded portions of both the deformable members 22 and 31 and because of the axial relation of the post and nut.

In all the constructions there is sufficient clearance space between the end of the post and the nut to apply in said space a non-corrosive medium, such as vaseline, and the threading of the nut downwardly over the threaded portion has the effect to compress the said medium intimately into contact with the contacting parts, as will be obvious from an inspection of Figures 3, 4 and 5. The space also serves as a retainer to hold a substantial quantity of said medium, and therefore keep the parts in condition for ready detachment and sepa-

ration of the parts.

While I have herein shown two embodiments of the invention differing in details from each other to effect substantially the same results, it will be understood that the invention is capable of other embodiments within the spirit and scope of the claim hereto appended.

I claim as my invention:—

A battery terminal connector comprising a split sleeve having at its upper end a threaded tapered outer surface, a nut adapted upon rotation to contract said sleeve upon a terminal post, a flange on the lower end of said sleeve and a wire receiving socket connected to said flange.

In witness whereof I claim the foregoing as my invention, I hereunto append my signature this 19 day of July, 1921.
